DISPLACEMENT PUMP

Robert E. Sykes, Sheboygan, Wis.

Application August 20, 1945, Serial No. 611,573

11 Claims. (Cl. 103—245)

1

The invention relates to fluid pressure operated pumps and the like and while not limited thereto it is especially applicable to liquid receiving and transmitting pumps operated by compressed gas acting directly upon the liquid, commonly known as displacement pumps.

Pumps of the aforementioned character have heretofore been provided with two displacement chambers, each having a suction and a discharge valve for the liquid and with a reversing valve for supplying pressure to each chamber and alternately exhausting the air therefrom, the arrangement being such that while one chamber was under air pressure the air in the other chamber was exhausted to the atmosphere, or was returned to the suction side of the air supply. The pumps aforescribed had the disadvantage that the discharge pressure of the fluid substance varied during the switching operation of the valve and they are therefore unsuited where a constant pressure of the discharge liquid is required.

The present invention has for one of its objects to provide a displacement pump in which the discharge pressure of the fluid substance is maintained substantially constant at all times.

Another object is to provide a displacement pump having a plurality of pump chambers whose operating cycles are so arranged that the discharge period of at least two chambers overlap in such a way as to assure a constant discharge stream of liquid substance.

Another object is to provide sequence control means for a multichamber displacement pump affording admission and discharge of the working fluid of the various chambers in regular sequence with overlapping of the discharge periods of consecutively discharging chambers.

Another object is to provide simple and efficient timing means for timing the operating cycle of the pump.

Another object is to provide pneumatic timing means which are operated by the pressure fluid which also furnishes the energy for operating the pump chambers.

Another object is to provide a plurality of pumps which may be operated in parallel or in tandem and supplied with working fluid controlled by a single timing or sequence control mechanism.

Another object is to provide means affording a constant liquid discharge pressure for varying discharge rates.

Another object is to provide for adjustment of the discharge pressure of the pump.

2

Another object is to provide a portable displacement pump.

Another object is to provide a portable displacement pump which can readily be adjusted to operate from different sources of pressure fluid.

Another object is to provide a displacement pump which is compact and small in size for its capacity and which can be installed in wells of various depths and of small diameter, or which can be inserted into a container through a small opening therein.

Another object is to provide a pump in which the several pump chambers are combined into an integral unit, while the timing and fluid control mechanism comprises another unit, both units being so arranged that they may be mounted together to form a unitary assembly, or the timing and control unit may be located apart from the pump unit and connected thereto by conduits of suitable length.

Another object is to provide a pump unit in which intermingling of the two fluids is avoided by preventing the conveyed liquid from entering into the pressure fluid supply conduit and the pressure fluid passing through the admission and discharge valves into the discharge conduit.

Another object is to provide a pump in which the maximum rate of discharge is limited.

Another object is to provide a pump in which the frequency of the operating cycle may be controlled.

Another object is to provide snap action pressure fluid operated pneumatic timing means for a pair of pressure fluid reversing valves controlling the supply of a pressure fluid.

Another object is to provide ready accessibility of the operating parts of a displacement pump.

Another object is to provide a displacement pump for conveying fluids of relatively high viscosity.

Another object is to provide a pump which consumes pressure fluid varying in accordance with the rate of liquid discharge, thus affording high efficiency for varying loads.

The accompanying drawings are illustrative of several embodiments of the invention. In the drawings

Fig. 1 is an elevation partially in section of a preferred form of the displacement pump.

Fig. 2 is a bottom view of Fig. 1.

Fig. 3 is a transverse section along the lines 3—3 of Fig. 1.

Fig. 4 is a vertical section along the lines 4—4 of Fig. 1.

Fig. 5 is a vertical section along the lines 5—5 of Fig. 4.

Figs. 6 and 7 are transverse sections along the lines 6—6 and 7—7, respectively, of Fig. 5.

Fig. 8 is a vertical section through the upper part of the pump in the same plane as the section Fig. 5.

Fig. 9 is a vertical section along the lines 9—9 of Fig. 8.

Figs. 10, 11, 12, 13, 14, and 15, are horizontal sections along the lines 10—10, 11—11, 12—12, 13—13, 14—14, and 15—15, respectively, of Fig. 9.

Figs. 16 and 17 are a vertical section along the lines 16—16 and 17—17, respectively, of Fig. 13.

Figs. 18 and 19 are diagrammatic showings of the coordination of the various elements of the pump illustrating the operation thereof.

Fig. 20 is a vertical section of a modification of certain parts shown in detail in Fig. 8.

Figs. 21 to 23, respectively, show diagrammatically various methods of installing the pump.

The apparatus illustrated in drawings Figs. 1 to 19, comprises a duplex displacement pump unit 40, and an air control and timing unit 41, connected with the pump unit as will be explained later. The pump unit 40 has two pump chambers 42 and 43 of like construction, one of which only needs to be described in detail.

The pump chamber 42 is provided at its lower end with a normally closed ball type fluid admission valve 44, having an inlet orifice 45 located in a foot casting 46. The ball 47 of valve 44 is arranged to engage a seat 48 interposed between the orifice 45 and a valve chamber 49 located in a bottom header casting 50, in line with the lower end 51 of the pump chamber. A spacer 52 attached to the upper end of the header 50 is provided with a bore 53 of like diameter as the bore 51 and coaxial therewith. Attached to the top of the spacer 52 in a liquid tight manner is a tube 54 which is semi circular in cross section and which forms the intermediate part of the chamber 42. The upper end of the tube 54 is attached in a liquid tight manner to an upper chamber header or manifold 55. The header 55 is provided with an orifice 56, through which the chamber 42 communicates with a threaded recess 57 extending downwardly into the manifold 55. A conduit 58 threadingly engages said recess 57. Arranged inside of the conduit 58 are two air conduits 59 and 60, one for each chamber. The conduit 59 communicates with the orifice 56, as will be explained hereafter. The lower header 50 is also provided with two ball type outlet valves 61 and 62 for the chambers 42 and 43, respectively. The outlet valve 61 is connected through a horizontal channel 63 with the chamber 49 and it is further connected to a liquid discharge conduit 64 which passes in a liquid tight manner through spacer 52. The upper end of the conduit 64 is connected through the upper header 55 to the recess 57. The connections of the chamber 43 are arranged in a manner similar to those of the chamber 42 as will be apparent from the drawings.

In the operation of the pump the unit is immersed into a liquid preferably so that the liquid surface is above the highest point of the upper header 55. Thereupon, if the conduits 59 and 60 are open to atmosphere, the liquid enters through valves 44 into the respective chambers 42 and 43, until the liquid inside of the chamber is level with the liquid on the outside of the pump. If now air under pressure is passed into the chamber 42 through the conduit 59, it displaces the liquid

therein, the valves 44 closing due to combined gravity and pressure, while the valve 61 is opened by the pressure of the liquid and the latter rises into the conduit 64 from where it is discharged as will be explained hereinafter. The air is supplied to the two conduits 59 and 60 alternately as will also be explained hereinafter. After the liquid in the chamber 42 has been emptied through the conduit 64, the supply of air to the conduit 59 is stopped and the air in the chamber 42 is permitted to exhaust to atmosphere or is sucked out of the chamber 42 to permit liquid to again fill the chamber, as aforescribed, and the cycle is repeated. The admission and exhaust of air from the conduits 59 and 60 is controlled by valves which are arranged in the timing unit 41.

The more detailed construction of the pump unit will now be described. The foot casting 46 is provided at its lower edge with a number of downwardly projecting feet 65, so arranged that when the pump rests on the bottom of a liquid container, liquid may enter under the foot casting 46 through the spaces between the feet 65. The casting 46 is further provided with a central recess 66, of large diameter into which open the orifices 45 of the admission valves 44. The lower end of the recess 66 is closed by a mesh screen 67, which prevents foreign matter carried by the liquid from entering the admission orifices. Interposed between the foot casting 46 and the bottom header 50, is a gasket 68 which has suitable openings for the connecting ducts. A valve seat 69, may be interposed between the cylindrical bore 51 and the valve chamber 49 for a purpose which will be explained hereinafter. A further gasket 70 is interposed between the header casting 50 and the spacer 52. Suitable screws 71, which extend through holes 72 in the extension 46 and in the header 50, and which engage tapped holes in the spacer 52 provide for the aligned assembly of the three last named parts into a unitary lower cylinder head.

The upper face of the spacer 52 is provided with two semi-circular grooves 73, into which are fitted the lower ends of the semi-circular tubes 54, and suitable packings 74, are interposed between said tubes and the spacer 52. The conduits 64 pass through bores 75 in the spacer 52, which are axially aligned with the valves 61 and 62, respectively. The lower ends of these bores are countersunk at 76 to a larger diameter to accommodate packing nuts 77. The packing nuts 77 are internally threaded to engage the threaded ends of the tube 54, so that upon screwing them on the tubes they pull the same downwardly into the spacer 52. Suitable packings 78 are interposed between the upper end of the packing nuts 77 and the shoulder of the bores 75, to provide a liquid tight joint. The packing nuts 77 are also provided at their lower end with a U-shaped stirrup 79, which affords means for turning the nuts and also affords a passage for the liquid into the conduits 64. The valve 61 is provided with a valve ball 80, the upward movement of which is limited by the stirrup 79. The countersunk hole 76 in the casting 52 is extended downwardly into the header 50 and is provided with a valve seat 81 for the valve 61, from which a bore 82 extends downwardly. The lower end of the bore 82 is closed by the gasket 68 and communicates through the horizontal channel 63 with the chamber 49. The extension of the bore 76 in the casting 50 also serves as a cage for the valve ball 80.

and permits the passage of liquid around and past the ball.

The lower face of the upper cylinder header 55 is provided with semi-circular grooves 83, similar to the grooves 73, to receive the upper end of the semi-circular tubes 54 and packings 84 are interposed between the end of the tubes 54 and the bottom of said grooves. The conduits 64 are threaded into the lower end of bores 85, which in turn communicate with the recess 57 and thus with the interior of the conduit 58. It will thus be apparent that after the conduits 64 are screwed into the casting 55 and the latter is assembled with the tubes 54, the spacer 52 and the packing nuts 77, the tightening of the latter clamps the tubes 54 tightly into the upper and lower seats, so as to assemble the top header 55 with the tubes 54 and the spacer 52 into a solid unit. Thereafter the bottom header 56 and the foot casting 46 with their component parts may be assembled and fastened together with the screws 71.

The bottom 86 of the recess 57 in the header 55 is also provided with two threaded holes 87, one each connecting with one of the orifices 56. The tubes 59 and 60, respectively, are threaded into said holes to provide a direct connection between said tubes and the pump chambers 42 and 43, respectively. The orifices 56 may each be provided with a valve seat 88, the purpose of which will now be explained.

It may be desirable to provide the pump with means which upon the discharge and admission of liquid by the pump chamber will prevent the passage of air to and through the liquid outlet valves 61 and 62 of the pump or the rise of liquid into the air supply conduits 59 and 60. For this purpose a cylindrical float valve 89, which is so proportioned that it will float in a substantially vertical position may be arranged in each pump cylinder as shown in dotted lines in Fig. 4. The valve is so proportioned that it is only partially immersed in the liquid. It is provided with conical upper and lower ends 90 and 91, respectively, to provide for cooperation with the valve seats 88 and 69, respectively, when the float has been moved to the corresponding end of the chamber by the liquid. The body of the float is of a diameter to afford free passage for the liquid between the float and the wall of the bores 53 and 54. Thus when the liquid in the cylinder 42 is at a certain low level, the lower cone 91 cooperates with the valve seat 69 to stop the flow of liquid into the compartment 49 which prevents the air above the liquid level in the cylinder 42 from entering into the said compartment. On the other hand, if the rising liquid level in the cylinder 42 approaches the valve seat 88, the upper cone 90 of the float cooperates with the valve seat 88 to provide a seal which prevents any further escape of air and the rise of the liquid beyond the valve seat 88 into the air conduit 59.

The air control and timing unit assembly 41 will now be described. The assembly comprises a housing made up of the following parts: a manifold casting 91, a manifold spacer 92, a valve housing 93, a top spacer unit 94, and a cover 95. The manifold unit 91 is a substantially circular casting provided with an axial bore 96, with reduced diameter at its lower end to provide an annular seat 97, intermediate of its ends. The bore 96 is tapped at its bottom end to receive the upper end of the conduit 58. A tapped bore 98, extends through the side of the manifold into the bore 96. The tapped bore 98 is adapted to receive a liquid outlet pipe 99, through which

the liquid under pressure is conveyed to its destination. A circular disc 100 is arranged to rest on the seat 97. The disc is provided with two bores 101 through which the upper ends of the tubes 59 and 60, respectively, extend. These tubes terminate approximately level with the upper face of the manifold 91. After the manifold is screwed on to the conduit 58, the conduits 59 and 60 are rigidly clamped to the circular disc 100 by means of a semi-circular plate 102, which is slightly larger in dimensions than the distance between the wall of the bore 96 and the outer wall of the respective tube 59 or 60. Clamping plate 102 is normally slightly tilted so that when it is pulled towards the disc 100 by means of a screw 103, which engages a threaded hole in the disc, said plate 102 forms a wedge to hold the tubes 59 and 60, respectively, rigidly in the disc.

The spacer 92 is mounted on top of the upper face of the manifold 91, a gasket 104 being interposed therebetween to provide a liquid and air tight joint. The spacer 92 is provided with two recesses 92a, into which the tubes 59 and 60, respectively, extend. Bores 92b extend from each recess through the spacer and a gasket 105 is interposed between the spacer 92 and the valve housing 93. Suitable packing rings 92c are interposed between the ends of the tubes 59 and 60 and the respective recess.

30 The manifold, spacer and the valve housing may be fastened together by means of headed screw bolts 106, which pass through suitable holes in the manifold and spacer and which engage tapped holes in the valve housing. At its 35 lower end the valve housing is provided with a circular recess 107 in which is mounted a metallic bellows 108. The bellows is closed at its lower end by a disc 109. An orifice 110 extends through the gaskets 104 and 105. The spacer 92 and the disc 109, together with orifice 108a in disc 109, provide a connection between the recess 96 and the inside of the bellows 108. The lower end of the bellows and the disc 109 are further provided with a circular flange 111 which is seated air tight in a counter bore 112 of the recess 107. The upper end of the bellows is provided with a circular disc 113 of suitable material arranged to be normally forced against a valve seat 114 inserted in a vertical bore 115, in the valve housing, the force being supplied by precompression of the bellows 108 upon assembly. The valve housing is also provided with a threaded inlet conduit 116 for the admission of air, which inlet is connected by a bore 117 with the recess 107.

55 The cylindrical valve housing 93 contains two horizontal high pressure admission valves 120 and 121, and two exhaust pressure valves 122 and 123, for controlling the air which actuates the timing mechanism for the pump control unit. 60 The valves 120 and 122 are mounted in axial alignment with each other and at right angle to the central axis of the valve housing 93. The valves 121 and 123 are also arranged in axial alignment with each other and with the first pair of valves, but below the latter. All four valves are alike in construction and it is therefore only necessary to explain the construction of one. The valve 120 has an inner valve chamber 124 and an outer valve chamber 125 with a valve seat 126 arranged intermediate of the two chambers. A cone shaped valve member 127 is provided with a central stem 128, the lower end of which is arranged to slide in a radial bore 129 extending into an axial recess 130 in the valve casing. The outer end of said valve stem pro-

vides a guide for a compression spring 131, which is interposed between the valve cone and the bottom of a recess 132 in a cover screw 133, which closes the outer valve chamber 125, the spring biasing the valve to the closed position.

The valves 120 and 121, 122 and 123, may be forced open by a concave barrel shaped cam 134, which is provided with an upward extension having circular grooves of V-shaped cross section 135 and 136. The upper end of the cam 134 is slideable in a bushing 137, which is shrunk into the bottom wall of the spacer unit 94. The spacer unit 94 is provided with a recessed circular chamber 138 extending from its upper face downwardly for purposes which will be explained hereinafter. Clamped between the spacer unit 94 and the cover 95 is a flexible circular diaphragm 139 of suitable material. The valve housing 93, the spacer unit 94, and the cover 95 may be aligned and assembled into a unit by cap screws 140, which extend through the cover 95 and the spacer unit 94 into tapped holes in the valve casing 93. A gasket 141 is interposed between the casing 93 and the spacer unit 94. The center of the diaphragm 139 is clamped between an upper diaphragm plate 142 and a lower diaphragm plate 143. The diaphragm and the upper diaphragm plate are each provided with a hole 144 through which passes a registering raised boss 145 on the upper face of the lower diaphragm plate 143.

The diaphragm and the upper and lower diaphragm plates are clamped together by a headed bolt 146, whose diameter is progressively reduced to form shoulders 147 and 148. The end of the bolt is threaded to engage a nut by means of which the diaphragm and the plates are rigidly held against the shoulder 148. The cover 95 is provided with a recess or chamber 149 to afford a space permitting oscillation of the diaphragm and the upper diaphragm plate. Said chamber is provided with a downwardly depending circular abutment 150, which limits the upward movement of the diaphragm by engaging the upper diaphragm plate 142. The lower diaphragm plate is bell shaped, the central part of its inner face being provided with an abutment surface 151, which is arranged to engage the upper end surface 152 of the actuating cam 134. The upper end of the actuating cam is provided with a central recess 153 in which is mounted a spring 154 which is under initial compression and is of such proportions that it can be further compressed until the surfaces 151 and 152 engage upon movement of the diaphragm. When said surfaces engage further downward movement of the diaphragm is directly transmitted to said cam. A central bore 155 in the cam provides for sliding engagement of the latter with the intermediate portion of the bolt 146, while the lower portion 156 of said bore is enlarged to form a recess for receiving a pre-compressed lower spring 157, which is arranged to abut the bottom of the recess 156 and the inner face of the head of the bolt 146. The two springs 154 and 157 are normally precompressed an equal amount so that the thrusts which they exert between the cam and the bolt are balanced. The shoulder 147 of the bolt 146 is adapted to engage the bottom of the recess 156 upon further compression of the lower spring 157. The bushing 137 is provided at its outer circumference with a circular groove 158, which houses a tension spring 159 arranged in the shape of a toroid. Coplanar with the groove

158 are a number of radial holes 160 extending through the wall of the bushing to house balls 161 which are urged by the spring 159 into the groove 135 or 136 of the cam, when the respective groove is coplanar with the groove 158. Thus the balls oppose movement of the cam in an axial direction in response to longitudinal thrusts of the springs 154 and 157, but when the surface 151 engages the surface 152 or the shoulder 147 engages the bottom of recess 156, the thrust on the cam 134 exerted by the diaphragm 139 is high enough to overcome the force of the spring 159 and to push the balls out of the grooves and thus permit the cam to yield to such pressure and move under the influence of the springs 154 and 157 until it is again arrested by the balls engaging the other groove. The concave surface 162 of the cam 134 is of such proportions longitudinally and diametrically that when (as shown in Fig. 9 in full lines) the stems of the valves 120 and 122 engage the cam at its smallest diameter, the stems of the valves 121 and 123 engage the same at one of its largest diameters and vice versa. In the position shown in full lines in Figs. 8 and 9, the cam is in its uppermost position and the valves 121 and 123 are open, while the valves 120 and 122 are closed. When the cam has been moved to the dotted position wherein the balls 161 engage the upper groove 136, the valves 120 and 122 are open, while the valves 121 and 123 are closed.

The passages for the air actuating the diaphragm 139 are as follows: As already pointed out air under pressure is admitted through the inlet 116 and passes thence through the bore 147 into the recess 107. The air exerts a pressure on the outside of the bellows 108 tending to compress it and if the resulting force is sufficiently in excess of the force due to the pressure exerted on the bellows by the liquid admitted to the interior through the orifice 110 and the precompression force on the bellows, the latter is compressed to separate the disc 113 from the valve seat 114 to admit air through the duct 115 to the horizontal duct 164, thence into a circular recess 165 in the valve housing 93, through the slanting duct 166, downward through the duct 167, to the outer valve chamber 125 of valve 120 and through the duct 167 to the outer chamber of the valve 121. The inner chamber 124 of the valve 120 is connected to the lower diaphragm chamber 138, through the vertical duct 168. The inner chamber of the valve 121 is connected to the upper diaphragm chamber 149, through the upwardly slanting duct 169 in the valve housing and shown in dotted lines. The duct 169 connects with the vertical duct 170 in the upper spacer 94 through the horizontal duct 171 which leads to the upper diaphragm chamber 149.

The upper diaphragm chamber is connected to the outer chamber of the valve 122 through the horizontal duct 172, the vertical duct 173, the horizontal duct 174 and the vertical duct 175.

The lower diaphragm chamber 138 is connected to the outer chamber of valve 123, through the slanting duct 176 and inwardly slanting duct 177 in the valve cage 93. The inner valve chambers of the valves 122 and 123 are connected to a common vertical duct 178. Said duct is provided near its lower end with a set screw 179, which may be screwed into said duct to more or less restrict it so as to afford an obstruction for the air flowing therethrough. The duct 178 connects to a horizontal duct 180, thence through

the horizontal ducts 181 and 182, to the air exhaust conduit 183.

The operation of the device is as follows: If with the apparatus shown in Figs. 8 and 9, air under pressure is admitted through the conduit 116, the pressure of the air opens the valve 114 and air is admitted through the passages already traced, through the valve 121 to the upper diaphragm chamber 149. The diaphragm thus is deflected downwardly thereby increasing the compression of the spring 154 and reducing the compression of the spring 157 and urging the cam 134 downwardly. But the cam is held in place by the locking action of the balls 161 in the groove 135, the excess thrust of the spring 154 not being sufficient to unlock the cam. When the diaphragm ultimately has been deflected by the air in the upper chamber to the extent that the surfaces 151 and 152 engage each other, its full thrust is exerted against the cam. This forces the balls 161 out of the groove 135, and the spring 154 moves the cam with a snap action until the shoulder 147 abuts the bottom of the recess 156. In this position the balls 135 under the impulse of the spring 159 drop into the groove 136 and thus again lock the cam, but now in its lowermost position.

While the cam was in its upper position the valve 122 was closed so as to cut off the escape of the compressed air from the upper diaphragm chamber. As already explained, the lower diaphragm chamber was connected with the inner valve chamber of the valve 123 in the original upper position of the cam. However, in this position the valve 123 is open, therefore the air in the lower diaphragm chamber, which is displaced by the downward movement of the diaphragm, can flow through the passages already traced to and through the lower valve 123 to the air exhaust 183. The speed of escape of the air and therefore the resistance offered to the downward movement of the diaphragm and thus its speed of movement may be regulatable by the adjustment of the screw 179. Obviously, instead of providing the adjustment screw 179 to throttle the air exhaust from the compartments 136 and 138, a similar arrangement may be substituted in the inlet duct 167 for the valves 120 and 121 for regulating the inlet pressure to the diaphragm compartments.

As soon as the cam has been moved to its lowermost position as described, the valves 121 and 123 close, while the valves 120 and 122 are opened. Thus the supply of compressed air to the upper diaphragm chamber and the exhaust of air from the lower diaphragm chamber are cut off. However, now the lower diaphragm chamber is connected to the source of compressed air through the valve 120, whereas the upper diaphragm chamber is connected to the exhaust conduit through the valve 122 and the diaphragm moves upwardly, the operation being apparent from the foregoing. Thus the diaphragm oscillates up and down at a rate which is determined by the adjustment of the rate of exhaust by the screw 179, the pressure of the air supplied through the conduit 116 and by the throttling effect of the valve 114, resulting from the action of the bellows 108. This action is as follows: If the pressure of the liquid at the delivery conduit 99 exceeds a certain value by stoppage or low rate of discharge of liquid so that the closing force of the bellows due to the liquid pressure exerted by the bellows 108 is greater than the opening force due to the air pressure on the

outside, the valve 114 partially closes thereby throttling the passage of compressed air to the diaphragm chambers, which in turn reduces the pressure differential between the two sides of the diaphragm and causes it to move slower and thus reduce the frequency of its oscillations.

For a full understanding of the control of the air supplied to the chambers 42 and 43 reference is made to the diagrammatic showings Figs. 18 and 19. As has been pointed out heretofore the diaphragm 139 and the diaphragm disc 143 oscillate cyclicly between an upper and lower limit. The total travel of the disc 143 may thus be divided from top to bottom into four equal zones A, B, C and D, as indicated in the drawing.

16 The air supplied to the chambers 42 and 43 is controlled by four spring biased normally closed valves (shown in detail in Figs. 16 and 17) as follows: An inlet valve 185 and a discharge valve 184 control the air for the chamber 42, and an inlet valve 187 and a discharge valve 186 control the air for the chamber 43. Each valve comprises a conical valve body cooperating with a valve seat which is interposed between an inner and an outer valve chamber. The valve 185 is provided with a valve stem at its inner end, said stem projecting upwardly through a suitable packed guide hole in the upper spaced 94. The stem is of such length that with the valve 185 closed a lower annular flange 188 of the diaphragm plate 143 makes contact with it to open the valve when said plate enters the zone B on the downstroke of the diaphragm and to maintain the valve open until the diaphragm on its succeeding upstroke returns to the same position. 20 The outer valve chamber of valve 185 is closed by the screw plug 189, which is provided with a recess to receive a compression spring interposed between the plug and the valve, to urge the latter to its closed position. The outer chamber of valve 185 is connected through a conduit 190, conduit 115, valve 114, recess 107, conduit 117 to air supply inlet 116.

25 The valve 184 is provided with an upward extending valve stem which is adapted to engage with a lost motion the flange 188 of the diaphragm plate 143, so that said valve is opened when the diaphragm plate enters the zone A on its up stroke and it stays open until said plate on its succeeding downstroke returns to the same position. A compression spring is interposed between the upper face of the valve and an abutment at the lower face of the upper spacer, said spring urging the valve to its closed position. The valve 186 is constructed similarly to valve 185, except that its valve stem is of such length that the valve is opened when the diaphragm plate enters the zone D on its downstroke and it is kept open until said plate on the succeeding upstroke reaches again the point of opening. 30 A compression spring is interposed between the lower surface of the valve and the gasket 185 to bias the valve to its closed position. The valve 187 is similar in construction to the valve 184, except that its stem is proportioned so that said valve 187 is opened when the diaphragm plate on its upstroke enters the zone C and is kept open until the diaphragm returns to the same position on its succeeding downstroke.

35 The outer chamber of the inlet valve 181 is connected through the slanting conduit 164 to the conduit 115, and thus over the path already traced to the inlet conduit 116. The inner chamber of the valve 181 is connected through the horizontal conduit 191, vertical conduit 192, the short connection 193 and one of the bores

11

92b to the tube 60. The outer chamber of the exhaust valve 186 is connected to the tube 60, through the horizontal connection 193 and one of the bores 92b. The inner chamber of the valve 186 is connected through the conduits 181 and 182 to the exhaust conduit 183. The inlet chamber of the valve 185 is connected through chamber 187, valve 114 and conduits 115 and 193 to the inlet conduit 116. The outer chamber of the valve 185 is connected through the horizontal conduit 194, vertical conduits 195, 196, and one of the bores 92b to the tube 59. The outer chamber of the outlet valve 184 is connected through the conduits 195, 196, and one of the bores 92b to the tube 59, while the inner chamber of said valve 184 is connected through the bores 198, 181 and 182, to the exhaust conduit 183.

The diagrammatic showing, Figs. 18 and 19, illustrate the control of the admission of air to and its exhaust from the pump cylinders. The valve 185 is the air admission valve and the valve 184 is the air discharge valve for the chamber 42, while the valve 187 is the air admission valve and the valve 186 the air discharge valve for the chamber 43.

Fig. 18 shows the diaphragm 139 in full lines on its upward stroke shortly after its reversal at its lowermost position. The cam 134 thus is in its lower position as has been described. The circular flange of the lower diaphragm plate 143 is in the position shown and maintains the admission valve 185 open, so that compressed air is passed into the cylinder 42 to force the liquid therein through the valve 61, conduit 64, conduit 58 and into the liquid outlet conduit 99. As the diaphragm 139 continues to move upwardly it opens the valve 187, thereby admitting compressed air into the cylinder 43 and forcing the liquid therein through the ball valve 62, conduit 58, into the discharge conduit 99, so that for a brief interval both cylinders 42 and 43 discharge liquid. Shortly thereafter the valve 185 closes thereby shutting off further delivery of compressed air to the cylinder 42. By this time the liquid in the cylinder 42 has reached its lowest level. As soon as the compressed air is shut off from the cylinder 42, the ball valve 61 closes. At the same time the valve 184 is opened, thereby relieving the air pressure in the cylinder 42 and permitting the air therein to exhaust through said valve 184, whereupon the pressure of the liquid in the tank T opens the valve 44 of cylinder 42 to again force liquid into the cylinder 42. During this upward movement of the diaphragm, the valve 187 remains open and the compressed air continues to push the liquid in cylinder 43 through the valve 62 into the exhaust conduit 99, the admission valve 44 of cylinder 43 remaining closed due to the excess pressure above said valve over the pressure of the liquid in the tank T.

After the diaphragm 143 reverses its movement from the upstroke in the manner already described, it moves down again to the position shown in full lines in Fig. 19 during which interval the valve 187 remains open so that the discharge of liquid from the cylinder 43 continues, while the cylinder 42 has been filled with liquid, the air in the latter cylinder having been exhausted through the valve 184. When the diaphragm reaches the position shown in full lines in Fig. 19, the valve 185 again begins to open and the valve 184 closes, so as to again cause discharge of liquid from the cylinder 42, as has

12

already been described. A brief interval thereafter the valve 187 is closed and the valve 186 is opened, thus again cutting off the supply of compressed air from the cylinder 43, to stop the discharge of liquid therefrom and thereafter permitting liquid from the tank T to fill the cylinder 43.

Thus it will be seen that the discharge of liquid from the two cylinders alternates, but so, 10 that there is an overlap during which both cylinders discharge liquid simultaneously. The pressure at which the liquid is discharged is substantially that of the pressure of the air supply and it is substantially constant due to the overlapping of the discharge from the two cylinders.

The pressure of the liquid at the discharge conduit 99 is somewhat affected by the friction 20 in the valves, the liquid and the air conduits. In order to regulate the liquid pressure further the 20 exhaust conduit 99 is connected, as described, to the interior of the bellows 108, while the compressed air inlet conduit 116 is connected to the chamber surrounding the bellows, so that the bellows is compressed or extended depending 25 upon the relation between the sum of the pre-compression pressure and internal pressure and the opposing external pressure acting on the bellows. If the pressure of the liquid increases 30 relative to that of the compressed air the bellows tends to close the valve 114 and vice versa. Thus the pressure delivered to the valves 120 to 123, inclusive, and 184 to 187, inclusive, is regulated in accordance with said differential pressure, thereby regulating the speed of operation 35 of the diaphragm and the speed of liquid flow through the pump chambers in accordance with the liquid demand. Furthermore, the amount of pressure fluid is varied in accordance with the amount of liquid discharged, thus conserving fluid 40 pressure and the corresponding energy to produce it.

To regulate the frequency of alternation of the diaphragm with respect to the speed with 45 which the liquid flows into the cylinders on the admission stroke, the set screw valve 179 in the air exhaust from the diaphragm chambers is provided. This valve permits the adjustment of the speed with which the diaphragm oscillates as has already been described. It is thus possible 50 to adjust the frequency of oscillation with respect to the maximum speed with which liquid is admitted into and exhausted from the cylinders to insure a substantially full stroke during the operation of the pump.

Fig. 20 is a modification of the mechanism 55 for actuating the cam 134 by the diaphragm 139. The lower diaphragm disc 143 shown in Fig. 8 is replaced by a modified disc 200, which is similar in shape to the disc 143, except that it is provided with a generally cylindrical extension 201, which projects downwardly below the circular flange 202, which latter corresponds in shape to the circular flange 138 of the disc 143. The bushing 137 in Fig. 8 is replaced by a bushing 65 203, which is provided with a number of radial bores 204 to receive the balls 161, which cooperate with the circular grooves 135 and 136 of the cam 134. The balls 161 are normally retained in the groove 135 or 136, respectively, by an internal circular cam surface 205 of the bushing 203, which is of such diameter as to normally lock the balls in one or the other of said grooves to hold the cam 134 in the respective position. As the diaphragm and with it the disc 200 move 70 down from the position shown, the balls are

forced outwardly due to the action of the spring 154 and 157 and slide over the conical surface 206 to ultimately engage the inner cylindrical surface 207, which is of larger diameter than the cam surface 205, thus releasing the balls from the respective groove and permitting the cam to move to its other extreme position as has been described heretofore. This, as will be apparent, causes reversal of the diaphragm. Upon the succeeding upward motion of the cam the balls are again locked in the respective groove by the cam surface 205. It will thus be seen that the cam is positively locked against movement in one or the other of its extreme positions during travel of the diaphragm and is only permitted to be moved thereby from its one extreme position to the other when the diaphragm is in its respective extreme position.

Fig. 21 illustrates the installation of the pump shown in Figs. 1 to 20 and described in connection therewith. The pump may be inserted in a barrel or tank T, and the air inlet conduit 116 and the air outlet conduit 183 connected to the delivery and the inlet ports, respectively, of a compressor C. By returning the exhaust air from the controller 41 to the compressor, the energy which is in the exhaust air is to a large extent recovered and therefore the device as a whole operates more efficiently. However, it is also possible to open the exhaust conduit 183 directly to atmosphere in which case the pressure of the exhaust air is that of atmosphere, while when the exhaust air conduit is connected to the suction end of the compressor the exhaust air pressure is below atmosphere. Connection of the exhaust conduit to the intake of the compressor is particularly advantageous for pumping high viscosity liquids, as it increases the speed of filling of the pump chambers and thus increases the capacity of the pump.

Fig. 22 shows another method of installation of the device. In this case the pump is installed at a level above that of the liquid contained in the barrel T, or in a well. In this case the return conduit 183 of the control unit 41 must be connected to the suction end of the compressor C so as to produce in the cylinders of the pump a suction head which will draw the liquid into the cylinder against the atmospheric pressure. Also the foot casting 46, instead of being open at the bottom, is closed. In other words, the recess 66 forms a closed chamber to which a suction pipe 250 which extends down into the liquid is attached. In all other respects the device is constructed the same and operates in the same manner as heretofore described. It will be apparent that the conduits 58, 59, and 60, which connect the control unit 41 with the pump unit 40 may be made in different lengths to provide for different distances of mounting between the pump unit 40 and the control unit 41.

Fig. 23 shows schematically two pump units 40 and 240 connected in tandem to lift liquid from a deep well W in two stages. The two units 40 and 240 may be controlled by a single control unit 41 supplied by a compressor C. The lower unit 40 is immersed below the level of the liquid and is controlled and functions in the same manner as the unit shown in Fig. 1. However, the liquid delivery pipe 99 of the unit 40 is connected to the bottom of the unit 240 which is provided with a closed foot casting similar to the unit shown in Fig. 22. The unit 240 in turn is provided with a liquid header and delivery pipe 299 which may extend a desirable distance above the top of the

pump unit 240. Air delivery pipes 259 and 260 with branches 59 and 60 extend from the controller 41 to the units 240 and 40, respectively. The compressor is connected in the usual manner to the air delivery conduit 116 and the air exhaust conduit 183 of the controller 41. The cylinders 42 and 43 of the lower pump unit 40 are filled by the liquid under the influence of the static head of the latter. On the exhaust stroke for the cylinders 42 and 43, compressed air is supplied to the cylinders by the conduits 59 and 60, respectively. The liquid thereupon rises in the conduit 99 and into the cylinders 242 and 243, respectively, from where it is delivered through the chamber 264 into the header and exhaust conduit 299. The delivery head of the two pumps H¹ and 2, respectively, depends upon the pressure of the air supply, the two heads being approximately equal though they may differ from each other.

The device operates in the following manner: Assuming that at the start the lower cylinders 42 and 43 are filled with liquid and pressure air is supplied through the conduit 259 and 59. This will force the liquid from the cylinder 42 into the conduit 99, while at the same time the cylinders 43 and 243 are connected through the conduit 260 and the controller 41 to the exhaust conduit 183. The liquid therefore will rise from cylinder 42 through conduit 99 into the cylinder 243 to fill the same. When the cylinders 42 and 243 are about filled the controller 41 operates in the usual manner to disconnect the conduit 259 from the high pressure air and connect it to exhaust, while the conduit 260 is connected to the high pressure air. Thereupon the cylinder 42 will again fill with liquid while the liquid in the cylinder 43 is now forced through the conduit 99 and into the cylinder 242. At the same time the air delivered to cylinder 242 forces liquid therein into the header 299. When the cylinders 43 and 242 are again filled and the cylinders 42 and 243 are again emptied, the air delivery to the conduits 259 and 260 is again reversed and the cycle is repeated. Thus it is apparent that by connecting the two pumps in tandem a much higher head of liquid can be overcome than by the use of the same pump, the pressure of the air supply being in both cases the same.

It will of course be possible to use more than two pump units in tandem, the operation being obvious. It will also be possible to operate the lower pump unit 42 with a suction head in the same manner as explained in connection with the arrangement Fig. 22.

It will be obvious that the delivery conduit 299 may be arranged for control of the inlet pressure of the air supplied through conduit 183 as explained in connection with Figs. 8, 18 and 19.

Other modifications within the scope of the present invention and the scope of the appended claims will be apparent to those skilled in the art.

What I claim as new and desire to secure by Letters Patent is:

1. In a displacement pump, in combination, a header, a plurality of displacement units each providing a chamber adapted to contain oppositely varying volumes of a fluid substance and a pressure fluid, each unit having non-return fluid admission and discharge means affording admission to the respective chamber of fluid substance from a source of such substance and alternatively discharge thereof from said chamber to said header in response to variations of the volume of pressure fluid in said chamber, joint pressure fluid and sequence control means oper-

able to afford periodic supply of pressure fluid to each chamber individually, with initiation of supply to each chamber prior to termination of such supply to at least one of the chambers preceding in sequence of operation and to effect withdrawal of such fluid from each chamber in the intervals between the respective supply periods, and means to regulate the speed of operation of said sequence control means independently of the supply of pressure fluid to said chambers.

2. In a displacement pump, in combination, a header, a plurality of displacement units each providing a chamber adapted to contain oppositely varying volumes of a fluid substance and a pressure fluid, each unit having non-return fluid substance admission and discharge means affording admission to the respective chamber of fluid substance from a source of such substance and alternatively discharge thereof from said chamber to said header in response to variations of the volume of pressure fluid in said chamber, and means operable cyclically to withdraw pressure fluid from the chamber and alternately supply pressure fluid thereto, sequence control means for the several of said plurality of cyclically operable means to effect sequential initiation of their operating cycles and initiation of supply of pressure fluid to each chamber prior to termination of supply of pressure fluid to at least one of the chambers preceding in the sequence of operation, and means to regulate the speed of operation of said sequence control means independently of the supply of pressure fluid to said chambers.

3. In a displacement pump, in combination, a header, a plurality of displacement units each providing a chamber adapted to contain oppositely varying volumes of a fluid substance and a pressure fluid, each unit having non-return fluid substance admission and discharge means affording admission to the respective chamber of fluid substance from a source of such substance and alternatively discharge thereof from said chamber to said header in response to variations of the volume of pressure fluid in said chamber, means operable cyclically to withdraw pressure fluid from the chamber and alternately supply pressure fluid thereto means responsive to the fluid level in said chamber to prevent access of pressure fluid to said fluid substance admission means and access of fluid substance to said cyclically operable means, and sequence control means for said plurality of cyclically operable means to effect sequential initiation of their operating cycles and initiation of supply of pressure fluid to each chamber prior to termination of supply of pressure fluid to at least one of the chambers preceding in the sequence of operation, and means to regulate the speed of operation of said sequence control means independently of the supply of pressure fluid to said chambers.

4. In a displacement pump, in combination, a header, a plurality of displacement units each providing a chamber adapted to contain opposite varying volumes of a fluid substance and a pressure fluid, each chamber having an admission valve affording admission of fluid substance from a source of such substance and a discharge valve affording discharge of fluid substance from said chamber to said header in accordance with variations of the volume of pressure fluid in said chamber and individual pressure fluid control means operable cyclically to withdraw pressure fluid from the respective chamber and alternately to supply pressure fluid thereto, a sequence

controller arranged to affect cyclic operation of the several of said pressure fluid control means with sequential initiation of their operating cycles and initiation of supply of pressure fluid to successive chambers prior to termination of supply of pressure fluid to at least one of the chambers preceding in the sequence of operation, and means to regulate the speed of operation of said sequence control means independently of the supply of pressure fluid to said chambers.

5. In a displacement pump, in combination, a header, a plurality of displacement units each providing a chamber adapted to contain opposite varying volumes of a fluid substance and a pressure fluid, each chamber having near its lower end an admission valve affording admission of fluid substance from a source of such substance and a discharge valve affording discharge of fluid substance from said chamber to said header in accordance with variations of the volume of pressure fluid in said chamber, a pressure fluid connection near the upper end of said chamber, individual pressure fluid control means operable cyclically to withdraw through said connection pressure fluid from the respective chamber and alternately to supply pressure fluid thereto, means responsive to the fluid substance level in said chamber to prevent access of pressure fluid to said admission valve and access of fluid substance to said connection, a sequence controller arranged to affect cyclic operation of said several pressure fluid control means with sequential initiation of their operating cycles and initiation of supply of pressure fluid to successive chambers prior to termination of supply of pressure fluid to at least one of the chambers preceding in the sequence of operation, and means to regulate the speed of operation of said sequence control means independently of the supply of pressure fluid to said chambers.

6. In a displacement pump, in combination, a header, a pair of displacement units each providing a chamber adapted to contain oppositely varying volumes of a fluid substance and a pressure fluid, each chamber having an admission valve affording admission of fluid substance from a source of such substance and a discharge valve affording discharge of fluid substance from said chamber to said header in accordance with variations of the volume of pressure fluid in said chamber and individual pressure fluid control means operable cyclically to withdraw pressure fluid from the respective chamber and alternately to supply pressure fluid thereto, a sequence controller arranged to affect cyclic operation of both of said pressure fluid control means with sequential initiation of their operating cycles and initiation of supply of pressure fluid to each chamber prior to termination of supply of pressure fluid to the other chamber, and means to regulate the speed of operation of said sequence control means independently of the supply of pressure fluid to said chambers.

7. In a timer and sequence controller for controlling the pressure fluid of a multi-chamber displacement pump, in combination, a casing having a cavity, a deflectable diaphragm mounted in said cavity and dividing it into two fluid tight compartments, a pressure fluid exhaust, snap action means operated by said diaphragm and adapted to connect one of said compartments to said inlet and the other to said exhaust alternately to afford corresponding alternate deflections of said diaphragm in opposite directions in response to the fluid pressure in said compart-

ments, a throttling valve connected in series with said reversing means and said outlet for regulating the flow of pressure fluid therethrough, individual reversing valve means for each chamber of the pump and operable by said diaphragm to sequentially connect the several chambers alternately to said inlet and said exhaust, a regulating valve connected to said inlet for regulating the pressure of the fluid supplied therethrough, a bellows connected to said valve for normally biasing it to closed position and having its outside subjected to the fluid pressure in said inlet to open said valve, and means to subject the inside of said bellows to the pressure of the liquid discharged by said pump to oppose the opening action of said fluid pressure.

8. In a timer and sequence controller for controlling the pressure fluid of a multi chamber displacement pump, in combination, a casing having a cavity, a deflectable diaphragm mounted in said cavity and dividing it into two fluid tight compartments, a pressure fluid inlet, a pressure fluid exhaust, a reciprocatory selector, a resilient motion transmitting connection between said diaphragm and said selector tending to maintain a given relative position therebetween and adapted to store up energy upon departure from said given relative position, a latch arranged to normally lock said selector at opposite ends of its travel against movement by said stored energy and to release said selector for response to said stored energy upon approach of said diaphragm of its extreme positions of travel, reversing valve means operated by said selector to connect one of said compartments to said inlet and the other to said outlet in one position of said selector and to connect said one compartment to said exhaust and said other compartment to said inlet in the other position of said selector to afford corresponding alternate deflections of said diaphragm in opposite directions in response to the fluid pressure in said compartments, a throttling valve connected in series with said reversing means and said outlet for regulating the flow of pressure fluid therethrough, individual reversing valve means for each chamber of the pump and operable by said diaphragm to sequentially connect the several chambers alternately to said inlet and said exhaust, a regulating valve connected to said inlet for regulating the pressure of the fluid supplied therethrough, a bellows connected to said valve for normally biasing it to closed position and having its outside subjected to the fluid pressure in said inlet to open said valve, and means to subject the inside of said bellows to the pressure of the liquid discharged by said pump to oppose the opening action of said fluid pressure.

9. In a displacement pump, in combination, a header, a pair of displacement units, each providing a chamber adapted to contain oppositely varying volumes of a liquid and a gas, each chamber having an admission valve affording admission of liquid from a source of liquid and a discharge valve affording discharge of liquid from said chamber to said header in accordance with variations of the volume of gas in said chamber and individual gas control means operable to withdraw gas from the respective chamber and alternately to supply pressure fluid thereto, a reciprocatory selector, an operative connection between said selector and each of said gas control means affording cyclic operation thereof upon

reciprocation of said selector with sequential initiation of their operating cycles and initiation of supply of gas to each chamber prior to termination of supply of gas to the other chamber, a diaphragm, means to subject said diaphragm to a cyclically varying gas pressure for deflecting it alternately in opposite directions, a resilient motion transmitting connection between said diaphragm and said selector tending to maintain a given relative position therebetween and adapted to store up energy upon departure from said given relative position, and a latch responsive to movement of said diaphragm and arranged to normally lock said selector at opposite ends of its travel against movement by said stored energy and to release said selector for response to said stored energy upon approach of said diaphragm of its extreme positions of travel.

10. In a fluid operated pressure pump unit of the class described adapted to be lowered in a well casing to the liquid to be pumped, a lower cylinder head providing a fluid admission, a plurality of chambers within said lower cylinder head, a fluid discharge valve for each of the chambers, an upper cylinder head providing an air conduit and a fluid discharge orifice for each of the chambers and a common fluid header for said orifices, a cylinder intermediate and joining said heads and comprising a plurality of parallel tubes respectively forming a corresponding second chamber, each tube connecting one of said fluid admission valves with a corresponding air conduit, and a liquid discharge conduit for each said first chamber interposed between the respective discharge valve and the corresponding fluid discharge orifice.

11. In a fluid operated pressure pump unit of the class described adapted to be lowered in a well casing to the liquid to be pumped, a lower cylinder head providing a fluid admission, a plurality of chambers within said lower cylinder head, a fluid discharge valve for each of the chambers, an upper cylinder head providing an air conduit and a fluid discharge orifice for each of the chambers and a common fluid header for said orifices and cylinder units selectively adapted to be disposed intermediate and to join said heads and comprising a plurality of liquid discharge conduits and corresponding tubes each forming respective second chambers, each tube connecting one of said fluid admission valves with a corresponding air conduit, a liquid discharge conduit for each said first chamber and being interposed between the respective discharge valve and the corresponding fluid discharge orifice, the respective tubes and conduits comprising said units being of different lengths whereby the capacity and operation of said pump may be adjusted.

Certificate of Correction

November 28, 1950

ROBERT E. SYKES

It is hereby certified that error appears in the printed specification of the above numbered patent requiring correction as follows:

Column 10, line 27, for the word "spaced" read *spacer*; line 48, for "strike" read *stroke*; column 16, line 69, after the word and comma "compartments," insert *a pressure fluid inlet*;

and that the said Letters Patent should be read as corrected above, so that the same may conform to the record of the case in the Patent Office.

Signed and sealed this 30th day of January, A. D. 1951.

[SEAL]

THOMAS F. MURPHY,
Assistant Commissioner of Patents.
